UNITED STATES PATENT OFFICE.

EDWARD A. FARISH, OF ST. JOSEPH, MISSOURI.

HITCHING-POST.

SPECIFICATION forming part of Letters Patent No. 429,123, dated June 3, 1890.

Application filed January 6, 1890. Serial No. 335,956. (No model.)

To all whom it may concern:

Be it known that I, EDWARD A. FARISH, a citizen of the United States, residing at St. Joseph, in the county of Buchanan and State of Missouri, have invented a new and useful Hitching-Post, of which the following is a specification.

The invention relates to improvements in hitching-posts.

10 The object of the present invention is to provide a simple and inexpensive hitching-post having a concealed hitching-strap that will remain normally within the post and will, when attached to a horse, have its weight 15 supported and prevented from drawing upon the mouth of the animal.

10 The invention consists in the construction and novel combination and arrangement of parts hereinafter fully described, illustrated 20 in the accompanying drawings, and pointed out in the claims hereto appended.

25 In the drawings, Figure 1 is a perspective view of a hitching-post constructed in accordance with the invention. Fig. 2 is a central longitudinal sectional view, the weight being shown supported and a strap being in position for use. Fig. 3 is a horizontal sectional view on the line xx , Fig. 4. Fig. 4 is a detail sectional view.

30 Referring to the accompanying drawings, 1 designates a tubular post whose lower end is adapted to be planted in the ground or to a suitable base 2, and whose upper end is threaded and provided with a cap 3, that 35 closes the upper end of the tubular post. The cap 3 is curved or slightly rounded and is provided with a central opening 4, in which is arranged a hitching-strap 5, whose free end is provided with a snap-hook that is adapted 40 to be attached to the bit of an animal. The lower end of the hitching-strap 5 is centrally secured to a disk 6, that is slightly larger than the bore or opening of the post and fits against the lower end of the latter and prevents the 45 hitching-strap 5 being entirely withdrawn from the post. The hitching-strap 5 is provided at a point about midway its length with a weight 7, that is adapted to draw the hitching-strap into the post and retain it concealed 50 therein, and when the strap is withdrawn for the purpose of holding an animal is designed to be supported by an annular flange 8, which

is arranged upon the inner wall of a tubular post near the top thereof. The annular flange 8 is provided with an opening 9, in which is arranged a section 10, that is attached to the end of a lever 11. The lever 11 extends through a slot 12 of the tubular post and is pivoted between two laterally-projecting ears 13 and is normally held horizontal by the section 10, which then lies in the same plane as the annular flange 8, and completes the latter and affords a support for the weight 7, which is preferably in the form of a ball. The section 10 of the flange weights the lever 11 and has its lower face beveled and adapted to be readily raised by the weight when the hitching-strap is withdrawn from the post, and quickly drops to its normal position when the weight 7 is slightly raised above it and securely locks the weight and prevents it drawing upon the mouth of an animal. The weight is readily released and allowed to fall and draw the hitching-strap within the post by tilting the weighted lever, and thereby removing the support.

From the foregoing it will readily be seen that the hitching-post is simple and inexpensive, is adapted to hold an animal without exerting a pulling force upon the mouth, and is capable of quickly drawing the hitching-strap within the post when desired.

Having described my invention, what I claim is—

1. The combination of the post provided near its top with a flange having an opening, the hitching-strap provided with a return-weight, and the automatic-locking device arranged in the opening of said flange, substantially as described.

2. The combination of the post provided with a flange having an opening, the weighted lever provided with the section 10, arranged in the said opening and completing the flange, and the hitching-strap having a return-weight, substantially as described.

3. The combination of the post provided near its upper end with a flange, the weighted lever, and the hitching-strap having its lower end secured to the bottom of the post and provided at a point about midway its length with a return-weight rigidly secured to it, substantially as described.

4. The combination of the tubular post pro-

vided with a slot 12 and laterally-extending-
ears 13, and having an annular flange provided
with an opening 9, and having its lower edge
beveled, the lever arranged in said slot and
5 pivoted between the ears and having the sec-
tion 10, completing the flange, and provided
with a beveled edge, the disk 6, secured at the
lower end of the post, the hitching-strap hav-
ing its lower end secured centrally to the
10 disk and provided at a point intermediate of
its length with a weight, and the cap having
a central opening, substantially as and for
the purpose described.

5. The combination of the tubular post
15 provided near its upper end with an annular

flange having its lower edge beveled and pro-
vided with an opening 9, the weighted lever
having the section 10, arranged in the said
opening and completing the flange, and the
hitching-strap secured to the disk and pro-
vided with a return-weight, substantially as
described. 20

In testimony that I claim the foregoing as
my own I have hereto affixed my signature in
presence of two witnesses.

EDWARD A. FARISH.
